UNITED STATES PATENT OFFICE.

WALTER RICHARD SMITH, OF NEW ORLEANS, LOUISIANA.

GAME TRAP.

Application filed May 6, 1922. Serial No. 559,001.

To all whom it may concern:

Be it known that I, WALTER R. SMITH, a citizen of the United States, residing at New Orleans, in the parish of Orleans and State 5 of Louisiana, have invented new and useful Improvements in Game Traps, of which the following is a specification.

The invention relates to a duplex or two-in-one game trap.

10 The object of the present invention is to improve the construction of game traps and to provide a simple, practical and efficient duplex game trap of strong and durable construction, equipped with two pairs of jaws 15 of different lengths, adapted to engage the different portions of a captured animal to prevent doubly the escape of trapped game, as the breaking off a foot in a single trap.

A further object of the invention is to 20 provide a duplex or two-in-one game trap of this character, in which the springs for actuating the two pairs of jaws will be nested one within the other and which may be compactly arranged for carrying or 25 transporting it from one place to another.

With these and other objects in view the invention consists in the construction and 30 novel combination and arrangement of parts hereinafter fully described, illustrated in the accompanying drawings and pointed out in the claims hereto appended, it being understood that various changes in the form, proportion and minor details of construction, within the scope of the claims, may be 35 resorted to without departing from the spirit or sacrificing any of the advantages of the invention.

In the drawings, in which like characters 40 of reference designate corresponding parts in the several views:—

Figure 1 is a plan view of a duplex game trap constructed in accordance with this invention, and shown set.

Figure 2 is a side elevation of the same, 45 partly in section, the trap being sprung.

Figure 3 is a sectional view on the line 3—3 of Figure 1.

Figure 4 is a detail perspective view of 50 the base of the trap.

55 Referring to the drawing, in which is illustrated the preferred embodiment of the invention, the duplex trap comprises in its construction two sets of jaws, a set of inner or short jaws 1 and a set of outer or long jaws 2, and the said jaws are hinged or pivotally mounted upon a single piece base

3 constructed of sheet metal or other suitable material of approximately T-shaped form. The laterally extending arms of the T-shaped base are provided with inwardly and 60 upwardly extending ears 5 and 6, the outer ears being formed by bending the terminals of the laterally extending arms upwardly and the inner ears being formed by splitting the metal of the arms longitudinally and 65 transversely and bending the partially severed portions upwardly in spaced relation and parallel with the terminal upwardly extending ears. The upwardly extending inner and outer ears are provided with bearing 70 openings 7 and 8 for the reception of the terminal pivot portions 9 and 10 of the inner and outer jaws 1 and 2. The inner and outer jaws are operated in spaced relation with each other and are adapted to 75 engage the captured game at different parts of the same, so that it will be impossible for the captured animal to escape from the trap by mutilating itself, which is often the case with a trap having a single set of jaws. 80

The jaws are actuated in their closing movement by inner and outer nested approximately U-shaped springs 11 and 12 located at one end of the trap and provided at their terminal portions with eyes or openings 13 85 and 14. The eyes or openings 13 of the inner spring 11 are of greater size than the openings 14 of the outer spring and are adapted to receive and permit the terminal portions of the inner spring to extend around both 90 sets of jaws and also both bearing ears at that end of the trap, as clearly illustrated in Figure 2 of the drawings. The openings or eyes 14 of the outer spring 12 are arranged on the outer bearing ear and the outer jaws 95 when the same are sprung. The tripping of the trap, after the latter has been set by the means hereinafter described, causes the springs to close the pivoted or hinged jaws 1 and 2 in the usual manner. 100

The trap is set by opening the jaws to the position illustrated in Figures 1 and 3 of the drawing and one of the outer jaws 2 is engaged by an outer trigger or catch 15, while the inner jaws are held open by engaging 105 one of the same with an inner trigger or catch 16. The engaged inner jaw also engages the free end of the trigger or catch 15 and holds the latter in engagement with the confined outer jaw 2. The inner trigger or 110 catch 16 is engaged by a setting lever 17 provided with a bait pan or treadle member

18 which is depressed by the game in attempting to obtain the bait, whereby the inner trigger or catch is released, permitting the inner jaws 1 to engage the game and the 5 release of the inner jaws 1 releases the outer jaws and permits the latter also to engage the captured game so that there will be no liability of the same escaping from the trap.

10 The arm 19 of the T-shaped base is provided with an outer laterally reduced portion 20 having a terminal ear 21 on which is pivotally mounted the outer trigger 15. The said arm 19 is provided at its intermediate portion adjacent the inner end of the 15 said reduced portion 20 with intermediate inner and outer upwardly extending ears 22 and 23 on which are pivotally mounted the inner trigger or catch 16 and the setting lever 17. The triggers or catches 15 and 16 20 are each pivoted or hinged at one end, preferably by being provided with an eye linked into an eye or opening in the supporting ears 21 and 22 respectively. The trigger 15 is swung over the adjacent outer jaw and 25 the adjacent inner jaw is then arranged upon the said trigger 15, while the inner trigger or catch 16 is arranged over the said adjacent inner jaw. The said lever 17 is pivoted or hinged to the inner intermediate 30 ear 23 in the same manner as the triggers or catches are hinged or pivoted to their supporting ears and it is provided adjacent the hinge or pivot with a shoulder 24 which engages and holds the free end of the trigger 35 or catch 16 until the bait pan or portion 18 is depressed by the weight of the game attempting to obtain the bait. The bait pan or treadle may be provided with any suitable means for the convenient attachment 40 of a bait. The openings or eyes of the springs will permit the same to be swung around to one side of the laterally extending arms of the base for folding the trap if desired.

45 5. What is claimed is:

1. A trap of the class described, including a base, inner and outer pairs of jaws hinged to the base, springs for actuating the jaws to close the same, an outer trigger or catch 50 arranged to engage one of the outer jaws and to extend beneath one of the inner jaws in setting the trap, a second trigger arranged to extend over the said inner jaw for holding the same, and a setting lever provided with means for engaging and holding the latter trigger and having bait holding means.

2. A trap of the class described, including a base of approximately T-shape, having 55 its laterally extending arms provided at

their terminals with inner and outer upwardly extending ears, the inner ears being formed by partially severing the material of the base, said base having its other arm reduced at the outer portion and provided 65 with an upwardly extending terminal ear and having intermediate inner and outer ears at the inner end of the said reduced portion, inner and outer jaws arranged in pairs and hinged to the inner and outer 70 ears of the laterally extending arms of the base, springs for closing the jaws, an outer trigger pivotally mounted on the terminal ear of the reduced portion of the base and arranged to engage one of the outer jaws, 75 an inner trigger mounted on the outer intermediate ear and arranged to engage one of the inner jaws, and a setting lever pivotally mounted on the inner intermediate ear and provided with means for engaging and holding 80 the inner trigger.

3. A trap of the class described, including a base, inner and outer pairs of jaws hinged to the base, means for setting the jaws, and a pair of approximately U-shaped nested 85 springs arranged at one end of the said jaws and provided with means for engaging and closing the same.

4. A trap of the class described, including a base, inner and outer pairs of jaws 90 hinged to the base, means for setting the jaws, and a pair of approximately U-shaped nested springs having terminal eyes or openings to receive the jaws, and the supporting means for the same at one end of the said 95 jaws.

5. A trap of the class described, including a base, inner and outer pairs of jaws hinged to the base, an approximately 100 U-shaped spring engaging one end of the outer pair of jaws and the support therefor, a second approximately U-shaped spring nested within the first mentioned spring and engaging one end of both pairs of jaws and the supports therefor, an outer trigger or 105 catch arranged to extend over one of the outer jaws and beneath one of the inner jaws in setting the trap, a second trigger arranged to extend over said inner jaw for holding the same, and a setting lever provided with means for engaging and holding 110 said second trigger, the arrangement being such that the force of both springs is upon the inner pair of jaws during the initial closing movement thereof and upon the outer pair of jaws after the jaws have been closed.

In testimony whereof I have hereunto set my hand.

WALTER RICHARD SMITH.
